FIG. 2

Inventor
Alder F. Connery
By Attorney W. J. Herdman

UNITED STATES PATENT OFFICE.

ALDER F. CONNERY, OF JAMAICA, NEW YORK, ASSIGNOR TO COMMERCIAL CABLE COMPANY, OF NEW YORK, N. Y., A CORPORATION OF NEW YORK.

SYNCHRONIZING SYSTEM.

Application filed October 22, 1926. Serial No. 143,471.

My invention relates to synchronizing systems and refers more particularly to synchronous telegraph systems used in connection with conductors of high electro-static capacity, such as for example long submarine cables.

The principal object contemplated by my invention comprises providing an improved means for utilizing distorted signals such as, for example, those received over long cables, for the purpose of synchronizing locally generated or reformed signals therewith.

Heretofore the synchronizing means used in connection with ocean cables have been very similar to the means used on land lines. These means of controlling synchronism from the received signals while satisfactory for land line apparatus are not entirely satisfactory when used with apparatus on ocean cables due to the peculiar signal distortion caused by the high electro-static capacity of the conductor.

In the unit or multiple-unit code which is in general use on ocean cables the various letters are formed by combinations of positive and negative impulses and the space between letters is indicated by an earthing or zero interval. The instant of operation of the receiving relays by a signal is influenced to a considerable degree by the character of the preceding signal. The arrival of a positive impulse, for example, will occur at a certain time if the preceding impulse was zero, but will occur a little later if the preceding impulse was negative. This effect is well known to cable operators and engineers.

Synchronizing systems heretofore used in conjunction with telegraph systems employed on ocean cables have been controlled by the instant of arrival of either dots or dashes or both. No account has been taken of the effect of the preceding signal on the signal from which correction is obtained. In my improved system I maintain the reformed or locally generated signals in synchronism with the received signals by means of received signals which are preceded by a signal of predetermined character only. Thus the instant of operation of the controlling mechanism is maintained constant and more reliable synchronism is thereby attained.

In the drawings which accompany and form a part of this specification, and in which like reference numerals designate corresponding parts throughout:

Fig. 1 illustrates diagrammatically the operating time sequence of the various elements of my system with reference to the current impulses necessary to transmit a sample word.

Fig. 2 illustrates diagrammatically an embodiment of my system adapted for use as a cable repeater.

Referring now to Fig. 1, line 1 shows diagrammatically the impulses forming the word Canadians as transmitted into the cable. Line 2 shows the shape of the received signals, while line 3 graphically represents the operation of the receiving relays by the received signals, from which it will be seen that a dot or dash following a space will cause the relays to operate earlier than if the dot or dash had followed a signal of opposite polarity, as for example, the first and last units of the letter C shown at *a* and *d* line 3 are longer than the 2nd and 3rd units shown at *b* and *c* on the same line. In other words the first and last units of each letter always have a tendency to run into the zero signal.

Referring now particularly to Fig. 2, I will describe one embodiment of my invention as applicable to a cable repeater. Signals are received over cable 1, which is balanced by the usual artificial cable 41, and operate the moving coil 2 which in turn causes contact 3 to slide over the surface of the revolving drum 4. The central portion of the drum 4 is insulated as shown and contact 3 normally rests on the insulated portion when the space or zero signal is received. When either a dot or dash is received contact 3 moves from the insulated portion of drum 4 to either one or the other of the metallic portions of the drum. Such receiving mechanism is well known in the art and needs no further explanation. When a dot is received make relay 5 and dot relay 6 will be operated, and when a dash is received make relay 5 and dash relay 7 will be operated. Make relay 5 operates when either a dot or dash is received while dot relay 6 only operates when a dot is received and dash relay 7 only operates in receipt of a dash.

A distributor comprising series of cams 8, 9, 10, 11 and 12 mounted in fixed angular relationship to each other on a shaft 30 is adapted to be driven by a synchronous motor. This motor which is not shown because its use is obvious to those skilled in the art,

is driven in the usual manner by contacts made by the vibrations of the tuning fork 13. The frequency of the fork 13 is so adjusted that the contacts of cams 8, 9, 10, 11 and 12 will when no current flows through the magnet 14 make slightly fewer contacts than the number of signal units received over the cable. When relay 15 closes its contact, magnet 14 is energized and the action of magnet 14 on the fork will cause the fork to reduce its amplitude and thus increase its frequency, thus causing the contacts operated by cams 8, 9, 10, 11 and 12 to make slightly more contacts than the number of signal units received over the cable.

Relays 15, 17, 21 and 22 are all polarized relays and are adjusted so that their armatures remain in contact with the contact last made until re-energized.

As break relay 5 is operated every time a dot or dash is received over the cable break relay 16 is similarly operated thereby. During the brief interval between the instant that the armature of relay 5 makes contact and the armature of relay 16 breaks contact current will flow through the armature of relay 5, the armature of relay 16, contacts of cutout relay 17, cam contacts S or F of cams 11 and 12 respectively and thence through windings 18 or 19 of relay 15 to ground. If cam contact S is closed when the impulse through the break relays 5 and 16 occurs, the armature of relay 15 will be thrown to the left as viewed in Fig. 2 and current through magnet 14 will be interrupted. The fork will therefore slow down and the cam contacts controlled thereby will make at a slower rate than the frequency of the received signal units. If, however, cam contact F is closed when the impulse through the break relays 5 and 16 occurs the armature of relay 15 will be thrown to the right as viewed in Fig. 2 and magnet 14 will be energized to cause the fork to make contacts at a higher rate and thus cause the cams to make and break their contacts at a faster rate than the frequency of the received signal units.

If the armature of relay 17 is held in a closed position the apparatus just described will maintain synchronism, but there will be considerable phase hunting caused by the variant distortion of the received signals as is the case in present systems which take no account of the character of the signal preceding the received signal. The purpose of relay 17 is to prevent signals other than those preceded by a signal of definite predetermined character from having any effect on synchronism by opening up the circuit from the break relay 16 at the proper predetermined intervals.

In the particular embodiment of the invention being described the apparatus and circuit comprising the system are arbitrarily

so designed that the only opportunity for synchronism correction is at the start of the first dot or dash after a space. To this end relay 17 opens after the first signal unit of a letter is selected, and the correction system is thus rendered inoperative until a zero signal is again selected. Referring to Fig. 2 the means which operate relay 17 will now be particularly described. When a dot is received dot relay 6 operates, cam contact 8 closes and current flows from positive battery through contacts of relay 6, through winding 20 of transmitting relay 21 and through winding 23 of relay 17 and cam contact 8 to ground. The armatures of relays 21 and 17 will be thrown to the right as viewed in Fig. 2, and an impulse will be transmitted from battery 50 to cable 40. Cam contact 9 closes at the same instant as cam contact 8. When cam contact 9 is closed current flows through winding 24 of relay 17 and tends to but does not throw the armature of relay 17 to the left as viewed in Fig. 2. If a dash is received relay 7 will be operated and relays 22 and 17 will be thrown to the right as viewed in the figure and a dash will be transmitted to cable 40. If any dots or dashes are now received the impulse generated by relays 5 and 16 at the start of each dot or dash will not get through to relay 15 because the circuit is open at the contacts of relay 17. If now a zero signal is received, relays 6 and 7 will not be operated, no current will flow through winding 23 of relay 17 and the armature of relay 17 will be thrown to the left by the weak current existing in winding 24 thereof, due to the closed condition of cam contact 7. The synchronism correcting circuit is now ready to respond to the next dot or dash received. If, for example, the next signal after a space or zero signal is a dot relays 5 and 6 will operate, relay 5 will cause relay 16 to operate and the short impulse of current through the armature of relay 16 will pass through the contacts of relay 17 and will throw the armature of relay 15 either right or left depending upon which of the contacts S or F, were at that instant closed. When cam 8 closes, relays 17 will open the synchronizing circuit.

The purpose of the contact operated by cam 10 is to restore transmitting relays 21 and 22 to normal just before each signal is selected and to thus give a short "earthing" interval on cable 40 between each dot or dash.

Referring now again to Fig. 1, line 4 shows the relative time sequence of the impulse through the armature of break relay 16. The operation of cutout relay 17 as shown on line 5 permits some of the impulses from the break relay 16 to pass and prevents others. The cutout relay 17 is so connected that it opens the circuit each time a dot or

dash is selected and closes the circuit every time a zero or space impulse is selected, thus the only opportunity for the correction of synchronism is at the start of the first dot or dash after a space.

It will be obvious that the impulses from the break relay 16 which are permitted to pass the cutout relay 17, all fall on the F corrector contact of the distributor as shown 10 by lines 6 and 7. All these impulses therefore keep the corrector relay armature in the right hand position as shown in Fig. 2 and current flows in the corrector magnet 14 as shown on line 8, and continues to flow 15 until the distributor is in phase with the frequency of the received signals.

While I have described but one embodiment of my invention and that with particular reference to a cable repeater it is to 20 be thoroughly understood that my device is not limited to such use, but may be used in numerous electrical systems requiring synchronism between received signals and those locally generated for further use.

Having thus completely described my invention what I claim is:

1. A three-element code synchronizing system comprising, signal receiving means, means co-operative with said receiving 20 means for generating potentially available signals in approximate synchronism with the received signals, and means for correcting the synchronism, said means being operable only by received signals which are preceded by a signal of predetermined invariable character.

2. A three-element code synchronizing system comprising, signal receiving means, means co-operative with said receiving 40 means for generating signals which are potentially available for further use, means for maintaining said generated signals in synchronism with the received signals, said means being operated by received signals 45 which are preceded by a signal of definite invariable character only.

3. A three-element code synchronizing system comprising, signal receiving means, means co-operative with said receiving means for generating signals which are 50 potentially available for further use, and means operated only by a received signal which is preceded by a signal of predetermined invariable character for maintaining 55 said generated signals in synchronism with the received signals.

4. A three-element code synchronizing system comprising, means for receiving signals, means co-operative with said receiving 60 means for generating potentially available signals approximately in synchronism with the received signals, and means operable only by received signals which are preceded by a signal of predetermined invariable character for bringing said generated 65 signals into full synchronism with said received signals.

5. A three-element code synchronizing system comprising, signal receiving means, means co-operative with said receiving 70 means for generating signals which are potentially available for further use and means operated only by a received signal which is preceded by a zero signal for maintaining 75 said generated signals in synchronism with the received signals.

6. A three-element code synchronizing system comprising, signal receiving means, means co-operative with said receiving 80 means for generating signals which are potentially available for further use, rotary means controlled by vibratory means for approximately synchronizing said generated signals with the received signals, and means 85 controlling said vibratory means and operated only by received signals which are preceded by a signal of definite invariable character for bringing said generated signals into full synchronism with said received signals.

ALDER F. CONNERY.
